UNITED STATES PATENT OFFICE.

WILLIAM L. WALKER, OF NEW YORK, N. Y.

SIGNALING DEVICE.

Application filed October 25, 1920. Serial No. 419,400.

To all whom it may concern:

Be it known that I, WILLIAM L. WALKER, a citizen of the United States, and resident of New York, in the county of New York and State of New York, have invented new and useful Improvements in Signaling Devices, of which the following is a specification.

This invention relates to signaling devices and while the devices are primarily intended to be used for submarine signaling they are also adapted to be used on automobiles and elsewhere.

The object of the invention is to provide a unitary signaling device which is simple and compact in structure, which is adapted to be used under water, which may be readily tuned to produce signals of any desired character, and which is efficient and economical in use.

In order clearly to disclose the nature of the invention I have shown by way of example certain concrete embodiments in the accompanying drawings, in which,

Fig. 1 is a plan of one embodiment of the invention;

Fig. 2 is a central longitudinal section of the embodiment shown in Fig. 1;

Fig. 3 is a section on line 3—3 of Fig. 2;

Fig. 4 is a section on line 4—4 of Fig. 2;

Fig. 5 is a section on line 5—5 of Fig. 2;

Fig. 6 is an end elevation of the embodiment shown in Fig. 1.

Fig. 7 is a central longitudinal section of a modification;

Fig. 8 is a similar section of another modification;

Fig. 9 is still another modification;

Fig. 10 is a section on line 10—10 of

Fig. 7;

Fig. 11 is a section on line 11—11 of Fig. 8;

Fig. 12 is a section on line 12—12 of Fig. 9;

Fig. 13 is a central longitudinal section of another embodiment of the invention;

Fig. 14 is a similar section of another embodiment;

Fig. 15 is a similar section of still another embodiment; and

Fig. 16 is a left end elevation of the embodiment shown in Fig. 13.

The particular embodiment illustrated on sheet 1 comprises a rectangular casing 1 which is preferably formed from a piece of brass tubing, the ends of the tube being

closed by plugs 2 and 3 which are tightly fitted into the ends of the tube 1. Mounted axially of the tube 1 is an electromagnetic structure comprising the laminated core 4 and energizing coils 5 and 6, the laminations of the core being disposed in vertical planes and the coils 5 and 6 being wound concentrically with the axis of the tube 1. The core 4 is provided with heads 7 and 8 at its opposite ends and with an enlargement 9 at the center, the windings 5 and 6 being disposed between these heads and the central enlargement 9. The laminations are secured together at the center and at the ends by rivets 4' the heads of which are seated in countersunk openings in clamping plates 4''. Mounted above and beneath the electromagnetic structure between this structure and the upper and lower walls of the casing 1, are vibrators 10, 11, 12 and 13, the vibrators 10 and 11 being formed integrally as a flat bar extending substantially the full length of the electromagnet and the vibrators 12 and 13 being similarly formed. These vibrators are spaced from the enlargement 9 of the magnetic core by means of spacers 14 and 15 and from casing 1 by means of spacers 16 and 17. The spacers 14 and 15 are preferably paramagnetic to form a magnetic connection between the case and the vibrators. Bars 18 and 19 extend transversely of the device above and below the central part 9 of the core and screws 20 extend through the bars 18 and 19, the casing 1, the bars 16 and 17, the vibrators 10, 11 and 12, 13, the spacers 15 and 16 and thence into the plates 4'' as shown in Fig. 3. Other screws 21 extend through the spacers 16 and 17, the spacers 14 and 15 and thence into the plates 4''. Anvils 22 are mounted along the inner walls of the casing, outside the free ends of the vibrators, by means of screws 23 extending into the end plugs 2 and 3.

The coils 5 and 6 may be connected either in parallel or in series but they are preferably connected in series, the two coils being shown in Fig. 3 as joined together by wire 5'. The terminals of the coils are connected to binding posts 24 and 25, as shown for example at 26 in Fig. 5, these binding posts being disposed in cavities 26 and 27 in the end plugs 2 and 3. Electrical cables 28 and 29 enter the cavities 26 and 27 through openings in the ends of the plugs 2 and 3 and the conductors of the cables connect with the binding posts 24 and 25 as shown at 30

in Fig. 5. The openings through which the cables 28 and 29 enter are rendered watertight by suitable packing glands 31 and 32.

The operation of the device illustrated on Sheet I is as follows. When alternating current or pulsating direct current is passed through the coils 5 and 6 vibrators 10, 11, 12 and 13 are caused to vibrate to and fro, thereby striking the anvils 22 and setting up vibrations in the casing 1 which vibrations are transmitted to the surrounding media. The coils 5 and 6 may be so connected that the end 7 of the core constitutes a north pole and the end 8 a south pole, in which case magnetic flux flows in the same direction throughout the entire length of the core at any given instant and thence flows in the opposite direction through substantially the entire length of the vibrators 10-11 and 12-13. However the coils 5 and 6 are preferably so connected that they are oppositely polarized, that is, a north pole for example being formed at 7 and likewise at 8 and each coil forming a south pole at the enlargement core at a particular instant. In this case the magnetic flux flows in opposite directions through the opposite ends of the core structure and thence in reverse direction through the vibrators back to the central enlargement 9. The outer casing 1 is preferably made of brass or other diamagnetic material so as to avoid shunting magnetic flux from the vibrators.

It will be obvious from the foregoing description that this device constitutes a very compact and permanent structure which is adapted for use as a signaling device in many situations and which is especially adapted for use in submarine signaling, inasmuch as it is thoroughly watertight and not subject to rapid deterioration when submerged. Devices such as these are adapted to be connected at intervals, of say one thousand feet, along a cable submerged along a waterway and when energized either in series or in parallel by alternating current transmitted along a cable they emit intense vibrations which may be detected by a ship traveling along the waterway to indicate the proper course. By varying the length of the tubular structure, by varying the length or weight or composition of the vibrators, or by otherwise adjusting the mechanical construction of the device it may be mechanically tuned to any desired period. Likewise by suitably proportioning the inductance of the magnetic circuit the electrical circuit may be tuned to the same periodicity thereby rendering the circuit resonant and much more efficient. The action of the cores would thus be similar to the action of loading coils on telephone circuits. In this case it would probably be

advisable to ground one end of the coils of each device to the case, the coils being thus all in parallel.

Figures 7 to 11 show a few of the many variations to which the present invention is subject. In Fig. 7, 33 represents an electro-magnetic structure of any suitable design, as for example that shown in Fig. 2. 34 represents an outer tubular casing which is cylindrical as shown in Fig. 10, and which is closed at the ends. 35 represents a tubular vibrator corresponding to the vibrators 10 to 13 in the first embodiment, these three parts being suitably positioned with respect to each other by means of spacers 36 and 37. The tube 35 is preferably spaced from casing 36 so that it strikes the outer casing, but its vibrations may be transmitted by the air between the two tubes or by the mounting compensation therebetween or in other suitable manner.

The modification shown in Figs. 8 and 11 is similar to that shown in Figs. 7 and 10, except in that the tube 35' corresponding to 35 of Figs. 7 and 10, is split on each side at each end as shown at 38, thus permitting the divided parts of the tube to vibrate independently toward and from each other much the same as in the case of the vibrators 10-13 in the first embodiment.

The embodiment shown in Figs. 9 and 12 differs from the preceding embodiment in that the electro-magnetic structure, indicated diagrammatically at 39, acts directly upon the outside casing instead of through the intermediary of one or more vibrators, the electro-magnet 39 being mounted directly in the casing 40 by means of spacers 41 and 42 disposed between the ends of the electromagnet and the ends of the casing. In order to increase the effective vibration of the casing 40 it is flattened into the form of an ellipse as shown in Fig. 12. Obviously any of the other embodiments may be thus flattened if desired.

The embodiments shown in Figs. 13-16 embody the same generic principle as the embodiment shown in the preceding figures, but they differ in that they are arranged to be actuated by mechanical means such as air, steam, exhaust from an internal combustion engine, or the like, instead of by electro-magnetic means.

The form shown in Fig. 13 comprises a cylindrical tubular casing 42 of steel or bronze, open at both ends, within which is mounted a frame or spider 43 by means of four screws 44. The spider 43 has an axial opening 45 and tubular extensions 46 and 47, the extensions 46 and 47 having openings 48 and 49 extending therethrough to the spaces 50 and 51. Fitted over the tubular extensions 46 and 47 are tubes 52 and 53, these tubes being spaced from the outer tube 42 by a very thin space of say .001 or .002 of

- an inch in thickness. The tubes 52 and 53 are closed at their ends by plugs 54 and 55, the plug 54 having a threaded opening adapted to receive a pipe 56. Upon supplying air, steam, exhaust gases from an internal combustion engine, or the like under pressure through the pipe 56 the gaseous fluid flows in part through the openings 48 to the space 50 and thence to the left through the thin space between the tubes 42 and 52, and in part through the axial opening 45, thence through the openings 49 to the space 51 and thence outwardly to the right through the thin space between the tubes 42 and 53. The flow of gaseous fluid through the thin spaces between the tubes 42 and the tubes 52 and 53 respectively causes the free ends of the outer tube 42 to vibrate and thereby set up signal disturbances.
- The embodiment shown in Fig. 14 comprises an outer casing 57, an inner tube 58, a ring 59 and plugs 60 and 61 and a fluid connection 62. The tube 58 has an annular raised portion extending around the central portion of its outer periphery, this raised portion having a thickness equal to the distance between the tubes 57 and 58, say from .001 or .002 of an inch. The parts are held together by screws 63 extending through the outer tube 57, thence through the thickened portion of the tube 58 and thence into the ring 59. On each side of the ring 59 openings 64 and 65 are provided in the tube 58. Upon admitting fluid under pressure to the interior of the device through tube 62 the fluid flows through the openings 64 and 65 and thence outwardly between the tubes 57 and 58, causing the free ends of the tube 57 to vibrate.
- The form shown in Fig. 15 is similar to that shown in Fig. 13 in that it comprises the outer tube 42', inner tubes 52' and 53', a spider 43' secured to the outer tube 42' by means of screws 44'. But it differs from the form shown in Fig. 13 in that the tubes 52' and 53' are made thinner and have no plugs in their free ends so that they may vibrate as well as the outer tube 42'; also in that tubular extensions 46' and 47' of the spider 43' are closed with plugs 65 and 66 and the pipe connection 62' is threaded into an axial opening in the plug 65. By arranging both the inner and the outer tubes to vibrate the intensity of the vibrations is considerably increased.
- The forms shown in Figs. 13 to 16 may be used either under water as submarine signaling devices or in air, as for example, automobile sirens. These devices may also be tuned by suitably proportioning the lengths of the tubes and the thickness and character of the materials.
- An important feature of the magnetic forms of the invention consists in that the air gaps are very small and consequently the magnet systems operate at a very high efficiency.
- I claim:
1. A signaling device comprising an elongate hollow member having a thin wall capable of vibration, and means supported substantially midway the ends of said hollow member and extending longitudinally in opposite directions from its point of support constructed and arranged to cause the opposite end portions of the hollow member to vibrate.
  2. A signaling device comprising a tubular member, an elongate vibrator supported substantially midway of the ends of the tubular member and extending in opposite directions from its point of support and means for actuating the vibrator.
  3. A signaling device comprising an elongate tubular member, closures for the ends of the tubular member, a support arranged substantially midway the ends of the tubular member, a vibrator secured to the support, electro-magnetic means for actuating the vibrator, said electro-magnetic means including conducting wires, and terminals for said wires carried by the end closures respectively of the tubular member.
  4. A signaling device comprising an outer tubular member and an inner vibrating member centrally secured to the tubular member and extending along the inner surface of said tubular member.
  5. A signaling device comprising a tubular member and means within the same providing diametrically opposed vibratory elements disposed closely adjacent to the inner surface of the tubular member and extending longitudinally of the member.
  6. A signaling device comprising a tubular member, closures for the ends of said member, a support intermediate the ends of said member, vibrators extending in opposite directions from the support and disposed closely adjacent to the wall of the tubular member, and electro-magnetic means for actuating said vibrator.
  7. A signaling device comprising a tubular member, an electro-magnet disposed concentrically within the tubular member, and vibrator members extending longitudinally of the tubular member at diametrically opposite ends thereof, said vibrator members being disposed between the magnet and the inner wall of the tubular member and closely adjacent to the latter.
  8. A signal including a casing, vibrators for setting up vibrations in the walls of the casing and a magnet mounted in the casing, fastening members passing centrally through the casing, magnet, and vibrators for securing the parts in assembled relation, and spacing members intermediate the casing and the vibrators and intermediate the vibrators and the magnet.

9. A signal device including a casing, vibrators and an actuating magnet, means for securing the magnet and vibrators within the casing, plugs forming closures for the casing, electrical connections carried by the plugs for completing the magnet circuit, and anvil members carried by the plugs and engaging the casing for transmitting vibrations from the vibrators to the casing.
10. A signaling device comprising a tubular casing, an electro-magnet concentric with the casing, there being an annular space between the magnet and the inner surface of the casing, and a pair of resilient vibrating bars of substantially uniform cross section from end to end disposed within said annular space at substantially diametrically opposite points, said bars being supported at one end and having their other ends disposed to engage the walls of the casing.
11. A signaling device comprising a tube, a magnetic core extending along the axis of said tube, windings extending transversely around said core, and vibrators extending longitudinally between said windings and said tube, said vibrators being centrally secured to the magnet and having free terminal portions actuated thereby.
12. A signaling device comprising a tube, a magnetic core extending along the axis of said tube, windings extending transversely around said core, and a vibrator extending longitudinally between said windings and said tube, said core having portions extending radially into juxtaposition to said vibrator at spaced intervals along the vibrator.
13. A signal device comprising a tube, a magnetic core extending along the axis of said tube, the core having radial projections at the center and ends, windings between said projections, and vibrators extending from said central projection into juxtaposition to said end projections for producing audible vibrations of the tube when intermittently actuated by the magnetic device.
14. A signal device comprising a tube, a magnetic core extending along the axis of said tube, the core having radial projections at the center and ends, windings between said projections, and vibrators extending from said central projection into juxtaposition to said end projections, said tube and core and vibrators being mechanically connected together at said central projection and actuation of the vibrators producing audible vibrations of the tube.
15. A signal device comprising a tube, a magnetic core extending along the axis of said tube, the core having radial projections at the center and ends, windings between said projections, and vibrators extending from said central projection into juxtaposition to said end projections, said tube and core and vibrators being mechanically connected together at said central projection and actuation of the vibrators producing audible vibrations of the tube.
16. A signaling device comprising a casing, an electromagnet within the casing, 70 said magnet having a core terminating in a head, an anvil secured to the wall of the casing opposite to said head but spaced therefrom, and a resilient vibrator supported by the casing and having a movable 75 portion disposed between the anvil and said head.
17. A signaling device comprising a vibrant tubular shell, a support fixed to said shell substantially at a nodal point of the 80 latter, and means carried by the support for setting the shell into vibration at either side of said nodal point, said means being tuned to impart vibrations to the shell having a period substantially equal to the natural period of vibration of the shell.
18. A signaling device comprising a vibrant elongate tubular shell having a central nodal point, a support secured to the shell at such nodal point, an elongate bar 90 secured midway its length to the support and having its free end portions disposed closely adjacent to the wall of the shell, and electro-magnetic means for vibrating the opposite ends of the bar simultaneously, the 95 electro-magnetic means being tuned to correspond to the natural period of vibration of the free ends of the bar.
19. A signaling device comprising an elongate casing, a plurality of parallel elongate diametrically opposed vibrator members arranged within the casing supported at points midway their lengths whereby the free end portions of each vibrator extend in opposite directions and parallel with the walls of the casing in close proximity thereto, and means for causing the free end portions of both vibrators to vibrate toward and from the adjacent wall of the casing.
20. A signal device including an elongate 110 tubular casing, a supporting member intermediate the length of the casing, vibratable members within the casing having portions immediately adjacent the casing at diametrically opposite portions thereof, said members being carried by the support and extending from the support toward the ends of the casing, and means disposed intermediate said parts for producing vibrations therein.
- Signed by me at New York, N. Y., this 7th day of October, 1920.

WILLIAM L. WALKER.
